F. H. FRANSON

CORE FOR CONCRETE FORMS

Filed March 9, 1926

Patented Aug. 10, 1926.

1,595,461

UNITED STATES PATENT OFFICE.

FRIITZ HUGO FRANSON, OF DENVER, COLORADO.

CORE FOR CONCRETE FORMS.

Application filed March 9, 1926. Serial No. 93,394.

This invention relates to a collapsible form which could be employed for a multitude of uses, such as a core for casting hollow building walls; or, in the manufacture of paper or textiles, it could be used as a form or mandrel upon which to wrap the material and for any other use desiring a form which can be collapsed and removed from the formed material.

10 The principal object of the invention is to provide a device of this character which can be readily contracted and yet which, when expanded, will withstand great pressure without collapsing.

15 Another object of the invention is to so construct the device that two or more of the forms may be inter-connected so as to act simultaneously, thus allowing it to be extended to any desired length.

20 A further object is to provide a form of this character which can be readily disassembled, without the use of tools, so as to occupy but a minimum of space when being shipped or transported.

25 A still further object is to provide means for extending the forms laterally as well as longitudinally by introducing co-acting sectional parts.

Other objects and advantages reside in the 30 detail construction of the invention, which is designed for simplicity, economy, and efficiency. These will become more apparent from the following description.

In the following detailed description of 35 the invention, reference is had to the accompanying drawing which forms a part hereof. Like numerals refer to like parts in all views of the drawing and throughout the description.

40 In the drawing:

Fig. 1 is a perspective view of my improved form.

Fig. 2 is a side elevation of two of the forms interconnected.

45 Fig. 3 is a plan view of the form, illustrating in solid line the collapsed position, and in broken line, the extended position.

Fig. 4 is a detail view illustrating the manner in which several of the forms may 50 be nested together for packing purposes.

Fig. 5 is an enlarged plan view of the inter-locking member.

The form comprises two U-shaped sections of sheet metal 10 and 11, joined together by 55 hinges 26 and hinge pins 12 and 13. The hinge pins 12 and 13 also secure a collapsible

cross brace to the hinges 26 of the sections 10 and 11. The cross brace comprises two brace members 14 and 15 of sheet metal having a length equal to that of the sections 10 and 11. 60 The inner edge of each brace member is turned at an angle forming feet 16 and 17, which project toward the center of the form, as shown in Fig. 3. Hinged between the feet 16 and 17 is a key member 18, shown in 65 Figs. 1, 3 and 5, by means of a second pair of hinge pins 19 and 20. The key member 18 comprises a sheet metal strip 21, the longitudinal edges of which are rolled at 25 to form the hinges for the hinge pins 19 and 70 20. Secured to opposite sides of the strip 21 are stiffening bars 22 and 23, which increase the torsional strength of the key member 18.

Let us assume the form is in the position 75 of Fig. 1; that is, extended. Should it be desired to contract the form to a smaller cross section so as to remove it from a surrounding substance, the key member 18 is turned, by means of a wrench or other suitable tool, in a clock-wise direction (looking downward). The rotating key member draws the cross braces 14 and 15 and the hinge pins 12 and 13 inwardly, thus reducing the width 80 of the form at its center and drawing the entire form inwardly, as indicated in Fig. 3. 85 This allows it to be readily withdrawn from a surrounding substance.

When in the extended position of Fig. 1, the feet 16 and 17 rest against the stiffener bars 22 and 23 of the key member 18, thus 90 effectively preventing the form from collapsing from external pressure.

Should it be desired to increase the length 95 of the form, two or more of the single forms of Fig. 1, may be joined together, as indicated in Fig. 2, by inserting longer hinge pins for the pins 12, 13, 19 and 20, that will pass entirely through the hinges of all the connecting forms. Should it be desired to increase the width of the form of Fig. 1, extension plates 27 may be inserted between 100 the edges of the U-shaped sections 10 and 11, as indicated in Fig. 2, and joined to these sections by means of the hinge pins 12 and 13. The forms may be still further extended 105 by inserting additional extension plates and joining them together by the hinge pins. When extending the forms laterally, collapsible cross braces are employed at each of the joining points of the various sections.

110 While a specific form of the improvement has been described and illustrated herein, it

is desired to be understood that the same may be varied, within the scope of the appended claims, without departing from the spirit of the invention.

5 Having thus described the invention, what I claim and desire secured by Letters Patent is:—

1. A contractible form comprising two sheet metal sections, U-shaped in cross section; pins hingedly joining said sections at their open extremities; a collapsible cross brace closing the open sides of said U, said collapsible cross brace comprising two sections hinged to said pins and projecting inwardly therefrom; and a third section hinged to said two sections.

10 2. A contractible form comprising two sheet metal sections, U-shaped in cross section; pins hingedly joining said sections at their open extremities; a collapsible cross brace closing the open sides of said U, said

collapsible cross brace comprising two sections hinged to said pins and projecting inwardly therefrom; and a third section hinged to said two sections, said third section having flat surfaces arranged to cooperate with flat surfaces on said two sections to prevent the structure from collapsing until said third section is rotated. 25

3. A contractible form comprising two sheet metal sections, U-shaped in cross section; pins hingedly joining said sections at their open extremities; and a collapsible cross brace closing the open sides of said U, said contractible cross brace extending throughout the length of said sections and comprising three members arranged to maintain alignment with each other until one of said members is rotated. 35

In testimony whereof, I affix my signature.

FRITZ HUGO FRANSON.
